US0D1063222S

(12) **United States Design Patent** (10) Patent No.: **US D1,063,222 S**
(45) Date of Patent: ** Feb. 18, 2025

(54) **PROTECTIVE HELMET**

(71) Applicant: **JINHUA CITY JINHAN SAFETY TOOLS CO., LTD.**, Jinhua (CN)

(72) Inventor: **Jun Xu**, Jinhua (CN)

(73) Assignee: **JINHUA CITY JINHAN SAFETY TOOLS CO., LTD.**, Jinhua (CN)

(**) Term: **15 Years**

(21) Appl. No.: **29/894,677**

(22) Filed: **Jun. 13, 2023**

(30) **Foreign Application Priority Data**

May 24, 2023 (CN) 202330310748.1
